UNITED STATES PATENT OFFICE.

OTIS W. EVERETT, OF WORCESTER, MASSACHUSETTS.

DESIGN FOR AN ICE-SKATE.

SPECIFICATION forming part of Design No. 33,931, dated January 15, 1901.

Application filed December 13, 1900. Serial No. 39,794. Term of patent 7 years.

To all whom it may concern:

Be it known that I, OTIS W. EVERETT, a citizen of the United States, residing at Worcester, in the county of Worcester and State of Massachusetts, have invented and produced a new and original Design for Ice-Skates, of which the following is a specification, reference being had to the accompanying drawing, forming a part thereof.

10 My invention relates to ice-skates, and particularly to what are termed "double-runner" ice-skates—that is, ice-skates having two parallel runners instead of a single runner.

15 My invention consists in a new and original design for a double-runner ice-skate, as will be hereinafter fully described.

The drawing is a perspective side view of a double-runner ice-skate, showing my design.

20 In the accompanying drawing the double-runner ice-skate has the body part or top 1 made in two parts *a* and *b*. The rear part *b*

has the upwardly-extending projections *c* on its rear end and the narrowed extension *d* at its front end and extending under the rear 25 end of the front part *a* and having a longitudinal opening *e* therein.

Extending down from the under surface of the body part 1 are the solid runners 2, arranged in two pairs—one pair at the forward 30 end on the part *a* and the other pair at the rear end on the part *b* of the body part 1.

The front pair of runners 2 have upwardly-curved projecting ends and the rear pair of runners have the rearwardly-extending downwardly-curved ends, as shown.

What I claim is—

The design for an ice-skate, substantially as shown and described.

OTIS W. EVERETT.
